UNITED STATES PATENT OFFICE.

JAMES H. NORTHRUP, OF TUSTIN, CALIFORNIA, ASSIGNOR TO THE DRAPER COMPANY, OF PORTLAND, MAINE, AND HOPEDALE, MASSACHUSETTS.

LOOM AND FILLING-CARRIER THEREFOR.

SPECIFICATION forming part of Letters Patent No. 638,200, dated November 28, 1899.

Application filed September 1, 1899. Serial No. 729,240. (No model.)

To all whom it may concern:

Be it known that I, JAMES H. NORTHRUP, a citizen of the United States, residing at Tustin, county of Orange, State of California, have invented an Improvement in Looms and Filling-Carriers Therefor, of which the following description, in connection with the accompanying drawings, is a specification, like letters and figures on the drawings representing like parts.

This invention relates more particularly to feeler-looms, wherein automatic filling-supplying mechanism is controlled as to its operation by or through a feeler which feels the filling in the shuttle and before the complete exhaustion of the filling effects the operation of the filling-supplying mechanism. A loom of this type is shown in United States Patent No. 626,187, dated May 30, 1899, wherein the filling is wound at or near the beginning of the spinning operation to form a well-defined projection or bunch for the feeler to work against, such bunch containing sufficient yarn to extend at least once across the lay. The feeler is withheld from effective operation by such bunch until it begins to wind off, and by such device a very small percentage of waste is involved.

In my present invention the filling-carrier is provided with a longitudinally-movable feeler-stop which is held in the path of and prevents effective operation of the feeler until the filling is exhausted to a predetermined extent, whereupon the stop is released and it is moved by its momentum out of the feeler-path when the shuttle is boxed. The winding of the yarn is such that when the feeler-stop is thus released there will be sufficient yarn still upon the filling-carrier to extend across the lay when the shuttle is thrown into the opposite box.

Figure 1 is a top or plan view, centrally broken out, of a sufficient portion of a loom to be understood with one embodiment of my present invention applied thereto. Fig. 2 is an enlarged side elevation, partially broken out, of the filling-carrier embodying my invention, the preliminary winding and a portion of the subsequent winding of the yarn being shown. Fig. 3 is a detail in elevation of the head end of a filling-carrier with the

feeler-stop in a different position, the filling-carrier being turned through ninety degrees relatively to Fig. 2; and Fig. 4 is a cross-sectional view of the filling-carrier on the line *x x*, Fig. 3, looking toward the right.

Referring to Fig. 1, the loom-frame A, breast-beam A⁴⁰, the lay A³, the self-threading shuttle S, the rotatable filling-feeder, (indicated by the letter F, Fig. 1, and comprising connected and suitably-shaped plates to receive the ends of the filling-carriers b,) the thread-supporting plate b', filling-end holder b², stud f, transference f', mounted thereon, and the shaft a', adapted to be rocked by movement of the filling-fork in the absence of the filling, may be and are all of well-known construction, like reference letters and numerals being herein used to designate like parts, as shown in Patent No. 626,187, referred to, and, as shown in said patent, the filling-feeder herein is located at one side of the loom and adapted to transfer a fresh supply of filling to the shuttle when in the shuttle-box B, the feeler mechanism located at the opposite side of the loom operating when the shuttle is in the box B'. As in said patent referred to, I have herein shown the filling-feeler a⁸ pivotally mounted at a⁹ and adapted to pass through an aperture 4 in the front wall of the shuttle-box B' (see dotted lines, Fig. 1) when the lay beats up.

If the shuttle be properly boxed, the feeler will pass through a slot 5 in the side wall of the shuttle and will bear upon the filling on the filling carrier or bobbin b at each beat of the lay until exhaustion of the filling to a predetermined point, pressure on the feeler tending to swing the arm a⁹ on its fulcrum to the left, Fig. 1, to prevent the co-operation of the dagger a¹⁵ with the blade a²³ to thereby effect through suitable intervening mechanism, such as described in said patent referred to, the rotation of the shaft d' and the operation of the filling-supplying mechanism.

So long as the feeler is engaged before a stud a¹⁸, mounted adjacent thereto, can pass through an aperture 6 in the wall of the shuttle-box and engage the side of the shuttle the dagger a¹⁵ will be maintained inoperative; but as the filling is drawn off a feeler-stop upon the carrier, and to be hereinafter de-

scribed, will be released and moved from the feeler-path, and the stud a^{13} will then engage first, so that the arm a^9 will be swung to the right, Fig. 1, to bring the dagger a^{15} into engagement with the blade a^{24} to thereby rock the shaft d' .

Referring to Figs. 2, 3, and 4, the filling-carrier b is represented as provided at its head end b^5 with the usual annular projections or 10 enlargements b^6 to enter suitable recesses in the holding-jaws of the shuttle, a cylindrical portion b^7 of the carrier adjacent the head being shown as provided with a longitudinal recess or slot b^8 , extending from one to the 15 other side thereof and intersecting the longitudinal bore b^{12} of the carrier. The feeler-stop, herein shown as a ring or annulus b^9 , is mounted to easily slide longitudinally along the portion b^7 of the carrier, said stud being 20 shown in Fig. 4 as provided with inturned and preferably yielding projections b^{10} , which enter the slot b^8 and serve to limit the movement of the feeler-stop, the latter being large 25 enough to present a considerable projection beyond the carrier.

Referring to Fig. 4, the projections b^{10} are shown as entering the bore b^{12} of the filling-carrier, and when the latter is placed upon the spindle in the spinning-frame said projections engage the spindle and hold the stop at the inner or right-hand side of the slot b^9 , viewing Fig. 2. When the spinning is begun, enough yarn y , Fig. 2, to extend at least once 30 across the lay is wound on the carrier above the stop b^9 , and then the yarn is wound below the stop, as at y' . Thereafter the traverse of the yarn both above and below the stop is carried on as usual until the desired amount 35 of yarn has been wound, holding the stop from movement and concealing the same. 40 Each time the shuttle enters the shuttle-box B' the feeler a^x will contact with the yarn which is wound over the feeler-stop, the normal position of the latter being in the feeler-path; and this will continue until all of the 45 yarn below the stop has been woven off or unwound. When this takes place and the stop has thus been released, it being remembered that only the preliminary wind y 50 of yarn now remains upon the filling-carrier, the said stop will by its momentum travel to the outer or left-hand end of the slot, viewing Figs. 2 and 3, when the shuttle is boxed in the left-hand end box B' , such position being shown in dotted lines, Fig. 2, and in full 55 lines, Fig. 3, and it will be manifest that at such time the stop will be out of the path of the feeler as the lay beats up, so that the stop a^{13} will engage the side wall of the shuttle 60 and swing or turn the arm a^9 on its pivot a^6 , there being nothing to prevent such movement. As the arm a^9 is thus swung to the right, viewing Fig. 1, the controlling means for the filling-supplying mechanism, including 65 the plate a^{23} and the rock-shaft d' , will be actuated, and the operation of the filling-supplying mechanism will be effected as the

shuttle is boxed in the box B at the right-hand side of the loom, so that a fresh supply of filling will be inserted in the shuttle.

The preliminary winding y of filling provides sufficient yarn to be carried across the lay after the effective operation of the filling-feeler, hereinbefore described, so that there will be no mispick or thin place in the cloth.

The percentage of filling-waste is by my present invention reduced to a very small proportion and the accuracy and rapidity of operation of the loom and the various parts hereinbefore described are increased.

While I have herein shown one practical embodiment of my invention and have chosen to illustrate it in connection with the feeler adapted to enter the shuttle through an aperture in the side thereof, my invention is not restricted thereto, for from an inspection of the drawings and the description hereinbefore set forth it will be manifest that my invention is equally applicable in any form of loom wherein a feeler is provided to intermittently feel the filling in the shuttle, said feeler being arranged to operate effectively as soon as a feeler-stop forming a part of or mounted upon the filling-carrier is moved out of the feeler-path upon exhaustion of the filling to a predetermined extent.

So far as I am aware it is broadly new to provide a filling-carrier with a movable feeler-stop, and consequently my invention is not restricted to the particular construction and arrangement herein shown and described, as the same may be modified or rearranged in various particulars without departing from the spirit and scope of my invention.

Having fully described my invention, what I claim, and desire to secure by Letters Patent, is—

1. In a loom, a shuttle, a filling-carrier therein having a longitudinally-movable feeler-stop, the filling being wound to retain the stop from movement until released by exhaustion of filling to a predetermined extent, filling-supplying mechanism, controlling means therefor, and a filling-feeler to govern the operation of said means, the stop when released moving out of the path of and permitting the effective operation of the feeler when the shuttle is boxed.

2. In a loom, a shuttle having a filling-carrier provided with an annular, longitudinally-movable feeler-stop, the filling being wound to retain the stop from movement until released by exhaustion of filling to a predetermined extent, filling-supplying mechanism, controlling means therefor, and a filling-feeler to govern the operation of said means, the stop when released moving out of the path of and permitting the effective operation of the feeler when the shuttle is boxed.

3. In a loom, a shuttle, a filling-carrier therein having a longitudinally-movable feeler-stop, a preliminary winding of the filling sufficient to extend across the lay being wound at one side of said stop, subsequent

- winding holding the latter from movement, filling - supplying mechanism, controlling means therefor, and a filling-feeler to govern the operation of said means, the momentum 5 of the stop, when released by exhaustion of the filling to the preliminary winding, moving it out of the path of and permitting effective operation of the feeler when the shuttle is boxed.
- 10 4. In a loom, a shuttle having a filling-carrier provided with a longitudinally-movable feeler-stop, a preliminary winding of the filling sufficient to extend across the lay being wound at one side of said stop; filling-supplying mechanism located at one side of the loom, controlling means therefor; and a filling-feeler at the other side of the loom, to govern the operation of said controlling means, the momentum of the stop when released by exhaustion of the filling to the preliminary winding moving the latter out of the feeler-path when the shuttle is boxed at that side of the loom, permitting operation of the feeler to effect a change of filling when the shuttle is 25 boxed at the opposite side of the loom.
5. As a new article of manufacture, a filling-carrier for looms, having a longitudinally-movable feeler-stop thereon.
6. As a new article of manufacture, a filling-carrier for looms, having an annular, longitudinally-movable feeler-stop thereon.
- 30 7. As a new article of manufacture, a filling-carrier having a longitudinal recess, and a feeler-stop movable on the filling-carrier
- and provided with a projection to enter said recess. 35
8. As a new article of manufacture, a filling-carrier having a longitudinally-movable feeler-stop thereon, and means to limit the movement of said stop. 40
9. As a new article of manufacture, a filling-carrier having a longitudinal slot near its head, and an annular feeler-stop embracing the filling-carrier and provided with inturned projections to enter the slot. 45
10. A filling-supply for loom-shuttles, comprising a filling-carrier having a longitudinally-movable feeler-stop, and a yarn mass, a preliminary winding of the yarn of sufficient length to extend across the lay being wound 50 upon the carrier at one end of the path of movement of the feeler-stop, the yarn thereafter being traversed at both sides of the stop and preventing movement thereof.
11. A filling-supply for loom-shuttles, comprising a filling-carrier having a longitudinally-movable feeler-stop thereon, and a yarn mass wound to hold the stop from movement until the yarn has been drawn off to a predetermined extent. 55

In testimony whereof I have signed my name to this specification in the presence of two subscribing witnesses.

JAMES H. NORTHRUP.
